Des. 237,907
Patented Dec. 2, 1975

237,907

PISTON FOR ENGINE

Darrell V. Gilliland, 1068 Bell St., Reno, Nev. 89503

Filed Dec. 10, 1973, Ser. No. 423,497

Term of patent 14 years

Int. Cl. D15—01

U.S. Cl. D77—1 A

FIG. 1 is a perspective view of a piston for engine taken from one side and end showing my new design;

FIG. 2 is a perspective view thereof taken from the side and end opposite to that shown in FIG. 1; and

FIG. 3 is a bottom plan view thereof.

I claim:

The ornamental design for a piston for engine, as shown.
